UNITED STATES PATENT OFFICE.

GEORGE L. BARRETT, OF SPRINGFIELD, OHIO.

DESIGN FOR A CALENDAR-BASE.

SPECIFICATION forming part of Design No. 34,925, dated August 13, 1901.

Application filed November 27, 1900. Serial No. 37,932. Term of patent 7 years.

To all whom it may concern:

Be it known that I, GEORGE L. BARRETT, a citizen of the United States, residing at Springfield, in the county of Clark and State of Ohio, have invented and produced a new and original Design for Calendar-Bases, of which the following is a specification, reference being had to the accompanying drawings, in which—

Figure 1 shows a plan view of a calendar-base, illustrating my design; and Fig. 2 is an edge view of the same.

As shown in the drawings, the leading or material feature of my design consists of a base having a circular body and a central circular portion ornamented and surrounded by three annular portions or panels, each subdivided into six equal sections by radial lines of outwardly-increasing width, the two inner annular portions being of about equal width

and the outer annular portions being of a considerably greater width.

In said drawings, 1 indicates the circular body; 2, the circular central portion; 3, the inner annular portion; 4, the intermediate annular portion; 5, the outer annular portion, and 6 the radial lines.

Having thus fully described my invention, what I claim as new, and desire to secure by Letters Patent, is—

The design for a calendar-base, substantially as herein shown and described.

In testimony whereof I affix my signature in presence of two witnesses.

GEORGE L. BARRETT.

Witnesses:

IRVINE MILLER,
E. O. HAGAN.
